UNITED STATES PATENT OFFICE.

WILLIAM P. TRIMBLE, OF COVINGTON, KENTUCKY.

BRAKE FOR RAILROAD-VEHICLES.

SPECIFICATION forming part of Letters Patent No. 437,531, dated September 30, 1890.

Application filed March 22, 1890. Serial No. 344,883. (No model.)

To all whom it may concern:

Be it known that I, WILLIAM P. TRIMBLE, a citizen of the United States of America, and a resident of the city of Covington, in the county 5 of Kenton and State of Kentucky, have invented certain new and useful Improvements in Brakes for Railroad-Vehicles, of which the following is a specification.

The several features of my invention and 10 the various advantages arising from their use, conjointly or otherwise, will be apparent from the following description and claims.

In the accompanying drawings, making a part of this specification, and to which reference is hereby made, Figure 1 is a view of the bottom of a railroad-car and of the running-gear of the same and of the mechanism embodying my invention combined therewith, the view being taken from the railroad-track, 15 looking upward. Fig. 2 is a vertical central longitudinal section of the drum or receptacle which contains the cone, cups, levers, and the annular ring portion of the levers, and showing in section one of the levers for operating the said cups, and also showing in vertical section the ring whereby the cup is connected to the said operating-lever, the operating-shaft passing through this drum or receptacle, and the chain-pinion and the car-axle, 20 D', pinion-wheel and the chain connecting these two chain-pinions being shown in elevation. The shaft for operating the said levers is also shown in elevation in this figure. Fig. 3 is a side elevation of the said chain, 25 the chain-wheel on the axle, and the chain wheel or pinion on the shaft operating the drum-cone, also showing portions of the chains which are wound upon the respective ends of the cups, and showing the main operating-bar 30 connecting the draw-heads and provided with springs, &c. Fig. 4 is a face view of the lever I and its connections.

The draw-head at one end of the car is indicated by the letter A, and the draw-head at 35 the other end of the car is also indicated by the same letter. The draw-bar is held longitudinally by any suitable means. One mode of support is shown and consists of the angulated support A², whose flanges are bolted to 40 the bottom of the platform of the car, sub-

stantially as shown. Between each draw-head and this support A², is located a suitable spring, as A', for enabling the draw-bar to gradually resist the impingement of the adjacent bar, and also to gradually resist a sudden pull upon the draw-head. Each of the draw-heads A is connected to the other by a draw-bar N, which passes under the platform of the car from the inner end of one draw-bar to the inner end of the other, and which is 55 suitably connected to its adjacent draw-head. At the ends of the car are the usual trucks containing two, four, six, or eight wheels, as the case may be. Suitable brake-bars E', of any suitable pattern, having brake-shoes E', 60 are present. These brake-bars may be adapted to be operated by any suitable mechanism consisting of rods or cords and levers, whereby a pull on one lever will assist in operating the brake. One other desirable system of 65 such levers and rods and chains is shown, and is as follows:

E⁶ is a lever centrally pivoted to the center of the inside of the platform C of the car. One limb of this lever is pivoted to a rod E⁵, 70 which extends toward the right-hand end of the car, and the other end of this rod E⁵ is pivoted to the lever E³ pivoted at E⁴ to the adjacent brake-bar E, or a suitable connection thereof, and at its other end pivoted to the 75 rod E², in turn pivotally connected to the brake-bar E. The other end of the central lever E⁶ is pivoted to a similar rod E⁵, extending toward the left-hand end of the car, and the left-hand end is pivotally connected to the 80 lever E³, in turn having its pivotal fulcrum in the brake-bar E, or a suitable connection thereof, as shown at E⁴. The other end of the lever E³ is pivotally connected to the rod E², extending toward the center of 85 the car and connected to a lever E¹², pivoted at E¹³ to its adjacent brake-bar E. The other end of the lever E¹² is pivotally connected to the rod E¹⁴, whose free end is connected to the stationary portion of the running car or 90 truck. It is desirable that at one end of the lever E⁶—as, for example, E¹⁰—the chain E⁷ should be connected. This chain extends to 95 one end of the car and is there wound upon the rod E⁸ of a hand-brake, constructed in 100

any of the well-known forms. The other end of the lever E^6 , as indicated here by the character E^{11} , is pivotally connected to a stud or rod E^5 .

- 5 In order to enable the lever to be operated by my device, hereinafter described, it is of course necessary that my device should be connected to the levers operating the brakes, and the preferred point of connection between my improved device and the brake-lever is at the point E^{11} of the central lever E^6 . This connection is made by means of the connecting link or rod E^9 , which, when desired, may be an extension of the rod E^5 .
- 10 15 The right-hand end of the rod E^9 is pivotally connected at F^8 to the lever F . One end F^8 of the said lever is pivotally connected to the stationary portion of the platform or running-gear of the car, while the other end F^2 is 20 pivotally connected to one end of each of the chains G G . The other end of one of these chains is wound upon the periphery of the extension G' of one of the friction-cups G^2 , and the other end of these chains is wound 25 upon the periphery of the extension G' of the other cup G^2 . A convenient means for the attachment of said chain to the cup is a staple, such as G^3 , shown in connection with the cup at the left-hand end of the cup in Fig. 2.
- 30 35 A receptacle or drum L is rigidly attached to the under side of the platform of the car. Through this receptacle there extends a shaft J . The shaft has a belt and rotates in journal-bearings L^3 L^3 of the drum or receptacle L , one of these journal-bearings being at one 40 end of the drum and the other at the other end of the said drum. One end of the shaft extends out beyond the end of the drum, and is there provided with a pinion J^3 , rigidly attached thereto. The teeth of this chain-pinion J^3 mesh with chain belt J^4 , also engaging with the teeth of the chain-pinion J^5 , rigidly connected to and concentric with the axle D' of one of the pair of wheels of the car. The 45 shaft J is prevented from slipping longitudinally in its bearings by means of any suitable device. One description of such device is shown, and consists of the rings $J'J'$, each of which rings being fixed to the axle by a 50 set-screw J^2 . One of these rings lies directly inside of the journal-bearings L^3 at one side of the drum, and the other of these rings is located directly inside of the journal-bearing L^{32} at the other end of the said drum. Within 55 said drum and mounted on the shaft is a friction-wheel H , one half H^2 representing the truncated friction-cone tapering toward the right, and the other H^3 representing the truncated friction-cone tapering toward the left.
- 60 65 These two wheels are united together at that end of each of them which has the largest diameter. These two portions of the friction-wheel H are rigidly connected together and form a single integral friction-wheel. This 65 wheel slides loosely upon the shaft J , and the shaft J would be free to revolve within the friction-wheel H without turning it were it

not for the stud J^6 , fixed to the said shaft J , which is located and operates within the slot H' . This slot H' is oblique to the longitudinal axis of the shaft J and extends equally into each half of the friction-wheel H , substantially as shown. On the right-hand side of this friction-cone there is a cup G^2 of such a size that when advanced toward its adjacent portion of the cone-wheel its inner periphery will tightly grasp the outer periphery of the cone-wheel and cause friction between the said surfaces. This cone-cup slides upon the shaft J and is provided with an extended portion G' , already mentioned, for receiving one of the chains G wound thereupon. A suitable means is provided for sliding this cup backward and forward upon the shaft, and consists of the lever I , as shown. This 80 lever I is at its lower end pivotally connected to the lower bottom portion of the drum L at I^6 by means of a suitable pivot, as I^4 . The central portion of the lever is formed into a ring, as I^5 . This ring I^5 encircles a smaller 85 ring I' . This smaller rings I' fits into a groove G^4 of the extension G^5 of the cup, which groove is preferably located at or near the outer end of the extension G^5 . The extension G^5 is loose 90 within the ring I' and can turn freely therein. The ring I' is pivotally connected to the ring I^5 of the lever I by suitable pivots, preferably such as I^3 , one of which is located on one 95 side of the ring I^5 and the other at the other side of the ring I^5 , each pivot I^3 being rigidly connected to the ring I' and extending through the slot I^2 in the ring I^5 of the lever I . The object of the slot in the ring I^5 is to allow the upper end of the lever I to freely reciprocate back and forth without binding 100 at the point where the pivot I^3 passes through it from the ring I' . Thus it will be seen that the lever I is free to be reciprocated back and forth in the direction of the longitudinal axis of the shaft J , and that it carries with it the 105 ring I' by means of the pivots I^3 , and at the same time moves the cup G^2 , to which the ring I' is connected, as aforementioned, also back and forth with it. At the upper side of the cone H is a similar cup G^2 , adapted to advance and frictionally engage the left-hand end of the cone-wheel H substantially in the same manner as the right-hand cup. This cup G^2 is provided with an extension G' , connected to the ring I' , in turn pivotally connected to the lever I in a manner similar to that in which the cone first named and its ring I' and lever I were connected. The second lever I is pivotally connected to the drum or cylinder at the lower end of said lever by 115 a pivotal connection, as I^4 . Through the upper portion of the drum or cylinder passes the shaft K . To this shaft K the upper ends of the levers I are connected. The upper end of the lever I is preferably bifurcated, and the rod K passes between the prongs of the lever. 120 125 130 135 Fixed to the rod K , to the left of the right-hand lever I , is a stud or projection K^3 , and

to the right of the left-hand lever I is a similar projection K³. When the rod K is moved from left to right, the projection K³ adjacent to the right-hand lever will move the latter 5 toward to the right hand, and when the rod K is moved from right to left the projection adjacent to the left-hand lever will move the latter toward the left hand. For the purpose of returning these rods in a contrary direction from that in which they have been moved by the studs K³, any elastic agency suitably located may be employed. A preferred means consist of spiral springs K² K² wound around the rod K. One of these springs is at the 10 right of the right-hand lever I and between it and the right-hand end of the receptacle L, (see Fig. 2,) and the other of these springs is at the left of the left-hand lever I and between it and the left-hand end of the receptacle L.

When the right-hand lever has been moved toward the right by rod K and stud K³ and the rod K is then moved toward the left, the adjacent spring K² will as soon as possible 15 return the lever I toward the left hand until it reaches the adjacent stud K³. In like manner the left-hand spring K² will return the left-hand lever I to the right after the latter, having been moved to the right by the rod K 20 and adjacent stud K³, is free to move to the right in consequence of the rod K having been moved toward the right. These springs have a tendency to keep the middle of that portion of the rod K which is between the studs K³ midway between the ends of the receptacle L. This rod K is reciprocated back and forth by suitable mechanism. The preferred description of such mechanism is as follows: 25 A right-angled lever having arms M² M² united together at right angles is pivoted at the point of junction of these two arms M² M², by a pivot M', to the platform or drum of the car. The free end of one of these arms M² M² is pivoted to the end of the rod K, as, 30 for instance, shown in Fig. 2, while the other end of the arm M² is pivotally connected to a sleeve N², sliding on the draw-bar, which connects the two draw-heads A. Between this sleeve N² and a ring N⁷, fixed to the draw-bar, 35 is located around the draw-rod N a spiral spring N⁴. The draw-bar N slides through the eye N⁵. One end of this spring N⁴ is preferably connected to the ring N⁷, and the other end thereof is preferably connected to the sleeve N². A spiral spring N⁶ is located 40 around the draw-bar between the sleeve N² and a ring N⁸, fixed to the draw-bar. One end of this spring is preferably connected to the sleeve N², and the other end of this spring N⁶ is preferably connected to the ring or connection N⁸, fixed to the draw-bar. Thus as 45 the draw-bar is drawn from right to left the spring N⁶ will be compressed and the spring N⁴ will be strained and move the sleeve from right to left, and when the draw-bar N is moved in the contrary direction the spring N⁴ will be compressed and the spring N⁶ will be

be strained and move the sleeve N², to which one end of the lever M² is pivoted, from left to right.

Between the right-hand friction-cup and the adjacent end of the cone is a ring J⁷, fixed to the shaft J. Likewise between the left-hand cup and the cone is a ring J⁷, fixed to the shaft J. When the cone is moved from right to left, the right-hand ring J⁷ prevents the adjacent right-hand cup G from following the cone all the way over and making frictional contact with it there. At the same time this ring does not prevent this right-hand cup from frictional contact with the cone when the latter has been moved toward the right. In like manner the left-hand ring J⁷ performs similar functions for the left-hand cup.

The mode in which my invention operates is as follows: Suppose the car is pulled or pushed through the agency of the draw-heads A' in the direction from left to right in Fig. 1. In overcoming the resistance of the car the draw-bar is moved from left to right a short distance, the springs A' allowing such movement of draw-heads and draw-bar. At the same time the draw-bar compresses the spring N⁴ and elongates the spring N⁵, and these in attempting to return to their normal condition—viz., in attempting to rid themselves of the compression and tension to which they are respectively subjected—move the adjacent end M² of the angular (or bell-crank) lever M² from left to right. The other end of this lever is thereby caused to move in Fig. 1 toward the top of the drawings and in Fig. 2 from right to left. This movement of the lever M² M² operates to draw the rod K, Fig. 2, from right to left. This causes the left-hand stud K' to impinge against the upper end of the left-hand lever I and move that lever I toward the left. The left-hand friction-cup is likewise thereby moved toward the left and out of reach of the friction-cone H, leaving the brakes out of contact with the wheels and the car perfectly free to move in the direction from left to right only. Whenever the pull upon the right-hand draw-head or the push upon the left-hand draw-head ceases, then the springs A' A' return the draw-bar A to its first position, and the lever M², through the agency of the springs N⁴ N⁶, is returned to its first position. This return movement of the lever M² moves rod K from left to right, and thereby allows the spring K² to force the left-hand lever I and its friction-cup G into frictional contact with the friction-cone H, which operation is immediately performed. Previous to this, and as soon as the car has started, the revolution of the car-wheel and its shaft D' has, through the agency of the chain-pinions J⁵ and J³ and the chain-pulley, rotated the shaft J. The rotation of the latter shaft has, by means of the slot H' and the stud or pin J⁶ therein, moved the friction-cone from right to left, as shown, and has consequently moved the latter within frictional reach of the

left-hand cup G^2 when advanced. By this frictional contact of the cone and the left-hand cup the rotary movement of the cone is imparted to this cup and the cone and cup revolve. As this cup revolves, the adjacent chain or cord G is thereby wound around the extension or sleeve G' of this cup. This shortens the said chain G and draws the lever F toward the right-hand end of the car, and through the connection E^9 , heretofore described, operates the lever E^6 and the system of brake mechanism aforementioned and applies the brake-shoes to the car-wheels. The car is thereby braked and brought to a stop. The brakes continue to press upon the wheels until the draw-bar is again operated upon in one direction or the other. Thus a car on an incline when detached from the rest of the train would not only be brought to a stationary position, but be kept in that position until the draw-bar was again forced forward or backward. Whenever this draw-bar is now subjected to a pull or push in either direction such movement of the draw-bar will operate to release the brakes, as follows: When the draw-bar is moved from left to right—viz., in the same direction in which the car was last moved—the lever M^2 and rod K and left-hand cup G^2 and sleeve G' will be moved as first hereinbefore described, the cup G^2 being moved to the left and freeing the cup from the said cone and allowing the cup to rotate and the chain G to unwind; but if the draw-bar should be moved from right to left the lever M^2 and rod K would be moved in a direction the reverse of that first described, and the right-hand lever I and its friction-cup will be moved from left to right. This movement will afford the cone an opportunity to be moved over from left to right, together with a partial revolution of the cone, and this partial revolution of the cone will relieve the pressure of the brakes upon the car-wheels. The cone has only moved a short distance from left to right, while the right-hand cup has moved a greater distance in the same direction. The cone is not in frictional contact with either cup. Hence the car is free to move until the force exerted upon the draw-bar from right to left ceases. The right-hand lever I will then, through the resilient movement of the springs N^4 and N^6 and the movement of the lever M^2 and the consequent movement of the bar K from right to left, be free to move its friction-cup over and into contact with the cone. The latter, on account of the rotation of the shaft in a direction the reverse of that first named, has been forced from left to right through the action of the slot H' and stud J^6 , and hence is near enough said cup to make frictional contact therewith and bring the car to a standstill. This position of the parts is indicated in Fig. 2. A subsequent longitudinal movement of the draw-bar N from right to left will operate to loosen the frictional hold of the right-hand cup G upon the cone and allow the latter to

rotate and the chain G to be unwound, these operations being similar to those hereinafter described in relation to the left-hand cup, the operations, however, being reversed.

The purpose of employing the springs N^4 N^6 to move the lever M^2 in response to the movement of the draw-bar is to relieve the lever M^2 and the other brake mechanism from the injurious shocks they might otherwise receive from the sudden movement of the said draw-bar.

The object of the double cup and cone and oblique slot is to prevent, when the car is moving in one direction, the brakes from being loosened by a pull or push upon the draw-bar in the opposite direction from that in which the car is moving.

A mechanical equivalent of the double cone centrally located between two cups would be a double-slotted cup centrally located between two cones. Such an arrangement of parts would successfully operate in the same manner as the double cone. I purpose to make use of either of these arrangements according as one or the other arrangement may be desired. So, also, the central cones or cups may be worked by a lever, the outlying members of the clutch having the slots.

What I claim as new and of my invention, and desire to secure by Letters Patent, is—

1. The draw-bar N , movable longitudinally and connected through elastic means to the end of the pivoted lever M^2 M^2 , the rod K , connected to the other end of the said lever M^2 , shaft J , suitably upheld and carrying double cone H , provided with slot H' , containing the stud J^6 , fixed on shaft J , and the friction-cups G^2 G^2 , each provided with the sleeve or extension G' , and mechanism, substantially as described, connected to the rod K and the said cups for reciprocating the same, substantially as and for the purposes specified.

2. The draw-bar N , movable longitudinally and connected through elastic means to the end of the pivoted lever M^2 M^2 , rod K , connected to the other end of the said lever M^2 , shaft J , suitably upheld and carrying double cone H , provided with slot H' , containing the stud J^6 , fixed on shaft J , and the friction-cups G^2 G^2 , each provided with the sleeve or extension G' , levers I I , each pivoted at I^4 to the receptacle or support L and provided with ring I^5 , inclosing the ring I' , pivotally connected to its friction-cup G^2 , rod K being provided with the stud K^3 and the springs K^2 , and means, substantially as described, whereby the rotation of the car-axle B' rotates the shaft J , substantially as and for the purposes specified.

3. The reciprocating draw-bar N and the sliding rod K and the mechanism intervening between draw-bar N and the said sliding rod for reciprocating the latter, spring K^2 , located between the right-hand lever I and the end of the receptacle L , adjacent stud K^3 of the rod K at the left of the said right-hand lever,

- and the left-hand spring K^2 , located on the rod K between the left-hand lever I and the left-hand end of the receptacle, and the adjacent stud K^3 , located at the right of the said 5 receptacle, receptacle L , supporting the shaft J , on which the latter slides, the double cone H , and the two friction-cups $G^2 G^3$, each provided with its extension or sleeve G' , levers I , pivotally connected to the ring I' , in turn 10 loosely connected to the extension G' of the friction-cups, the friction-cone H being provided with slot H' , receiving stud J^6 of the shaft J , and chains G , respectively attached at one end to the sleeve G' and at the other to 15 the lever, connected to the brake system of the latter, shaft J receiving rotary motion by means, substantially as described, with one of the car-axles, as D' , substantially as and for the purposes specified.
- 20 4. The reciprocating draw-bar N and the sliding rod K and the mechanism intervening between draw-bar N and the said sliding rod for reciprocating the latter, spring K^2 , located between the right-hand lever I and the 25 end of the receptacle L , adjacent stud K^3 of the rod K at the left of the said right-hand lever, and the left-hand spring K^2 , located on the rod K between the left-hand lever I and the left-hand end of the receptacle, and the 30 adjacent stud K^3 , located at the right of the said lever, receptacle L , supporting the shaft J , on which the latter slides, the double cone H and the two friction-cups $G^2 G^3$, each provided with its extension or sleeve G' , levers I , 35 pivotally connected to the ring I' , in turn loosely connected to the extension G' of the friction-cups, the friction-cone H being provided with a slot H' , receiving stud J^6 of the shaft J , ring J' , fixed to shaft J , being interposed between each friction-cup and the adjacent side of the friction-cone, and chains G , 40 respectively attached at one end to the sleeve G' and at the other to the lever connected to the brake system of the latter, shaft J receiving rotary motion by means, substantially as and for the purposes specified.
- 45 5. The sliding draw-bar N and the car platform or frame C , the latter provided with eye N^5 and the stationary point N' and the sleeve N^2 , sliding upon the draw-bar N between the eye N^5 , point N' , and connected to one end of the lever M^2 , spring N^4 , located between and connected to the sleeve N^2 and the eye N^5 , 50 and spring N^6 , located between and connected to the sleeve N^2 and the point of connection N' , lever M^2 , pivotally connected to sliding rod K , levers I , springs for returning the said levers to position, studs K^3 on the rod K , friction-cone H , with slot H' , and the shaft J , 55 having stud J^6 located within the said slot H' , the levers I , each pivoted to the ring I' , in turn respectively connected to the adjacent portions G' of the friction-cups G^2 , one located on one side and the other located on the other side of the said friction-cone H , and chain G , connected to the brake system, and gear or pulley connections between the car-axle D' and the shaft J^2 for imparting rotary motion to the latter, substantially as and for the purposes specified.
- 60 6. The double friction-cone having the oblique slot H' , located partly in one incline of the cone and partly in the other incline of the cone, containing the stud J^6 , fixed to the shaft J , friction-cups $G^2 G^3$, one located in one side and the other in the other side of the said double friction-cone H , provided with sleeves J' for winding thereon chains or cords, 65 as G , levers I , respectively connected to the said friction-cups and for reciprocating the same, and connected by intermediate mechanism, substantially as described, with the reciprocating draw-bar N , substantially as and for the purposes specified.
- 70 7. Car-shaft D' , shaft J , connected to shaft D' , operated thereby, in combination with cones $H^2 H^3$ and cups $G^2 G^3$, levers for approximating a cup and its respective cone, draw-bar, and intervening mechanism, substantially as described, intervening between the draw-bar and the levers, substantially as described, for operating these levers.
- 75 8. In a railroad-vehicle, and in connection with a brake and a friction-clutch composed of two cups and two cones, a slot provided in either the cups or cones of said clutch, together with a pin or short thread on the said shaft working in the said slot for the purpose of shifting the same back and forth upon the shaft according to the direction in which the shaft may be revolving, and the levers for operating the other member—viz., the cups or cones not shifted by the oblique slot—substantially as and for the purposes specified.
- 80 9. Car-shaft D' , shaft J , connected to shaft D' , operated thereby, in combination with cones $H^2 H^3$ and cups $G^2 G^3$, levers for approximating a cup and its respective cone, draw-bar, and intervening mechanism, substantially as described, intervening between the draw-bar and the levers, substantially as described, for operating these levers.
- 85 10. Car-shaft D' , shaft J , connected to shaft D' , operated thereby, in combination with cones $H^2 H^3$ and cups $G^2 G^3$, levers for approximating a cup and its respective cone, draw-bar, and intervening mechanism, substantially as described, intervening between the draw-bar and the levers, substantially as described, for operating these levers.
- 90 11. Car-shaft D' , shaft J , connected to shaft D' , operated thereby, in combination with cones $H^2 H^3$ and cups $G^2 G^3$, levers for approximating a cup and its respective cone, draw-bar, and intervening mechanism, substantially as described, intervening between the draw-bar and the levers, substantially as described, for operating these levers.
- 95 12. Car-shaft D' , shaft J , connected to shaft D' , operated thereby, in combination with cones $H^2 H^3$ and cups $G^2 G^3$, levers for approximating a cup and its respective cone, draw-bar, and intervening mechanism, substantially as described, intervening between the draw-bar and the levers, substantially as described, for operating these levers.
- 100 13. Car-shaft D' , shaft J , connected to shaft D' , operated thereby, in combination with cones $H^2 H^3$ and cups $G^2 G^3$, levers for approximating a cup and its respective cone, draw-bar, and intervening mechanism, substantially as described, intervening between the draw-bar and the levers, substantially as described, for operating these levers.
- 105 14. Car-shaft D' , shaft J , connected to shaft D' , operated thereby, in combination with cones $H^2 H^3$ and cups $G^2 G^3$, levers for approximating a cup and its respective cone, draw-bar, and intervening mechanism, substantially as described, intervening between the draw-bar and the levers, substantially as described, for operating these levers.
